STAY FOR CORSETS

Isidore Panes, New York, N. Y.

Application November 15, 1944, Serial No. 563,498

2 Claims. (Cl. 2-36)

1

This invention relates to stays which may be used advantageously for garments, such as corsets.

The principal object of the invention is the provision of an improved construction whereby resilient stays are incorporated in a garment so that the stays will not be kept abnormally flexed due to shrinkage of the material of the garment.

A further object of the invention is the provision of improvements whereby stays are kept from shifting out of a functioning position.

A further object is the provision of an improved construction for incorporating stays of the indicated character in the aforesaid manner, and wherein the stays are padded or reenforced at the ends so as to prevent puncturing of the material which encloses the stays.

The nature of the invention and its distinguishing features and advantages will appear when the following specification is read in connection with the accompanying drawing, in which—

Fig. 1 is a fragmentary view showing part of a corset with the stays incorporated according to the present invention, a portion of the stay pockets being broken away.

Fig. 2 is a sectional view taken on the line 2—2 of Fig. 1.

Fig. 3 is a view of one end portion of a stay and the material for securing, padding and reenforcing the end portion, said material being shown unfolded.

Fig. 4 is a view similar to Fig. 3, but showing the securing, padding and reenforcing material folded over the end portion of the stay.

Figs. 5 and 6 are sectional views taken on the lines 5—5 and 6—6 of Figs. 3 and 4, respectively.

Figs. 7 and 8 are sectional views taken on the lines 7—7 and 8—8, respectively, of Fig. 1.

In the drawing, a part of a garment, such as a corset, is designated 10. In such garment stays are used at spaced positions to preserve the shape of the garment and to aid in embracing and supporting parts of the wearer's anatomy. According to the present invention, one or two stays are retained in a pocket structure secured to the material of the garment. In the present instance, according to the invention, a pair of stays is arranged in double pocket structure and any suitable number of such pocket structures may be used and applied either to the outside or inside of the garment.

Each stay 11 is in the form of a narrow strip of resilient material, such as steel, whalebone, wood or any other suitable material. To each

end portion of the stay 11 is applied suitable material which serves as a means to secure the stay in place, to reenforce the securement, to pad the ends of the stay, and to prevent the ends 5 of the stay from puncturing the material of the garment. The material used for the aforesaid purposes in the present instance is cloth or textile fabric. A piece of the fabric is applied to each end portion of the strip 11 by folding the 10 piece lengthwise upon itself and the longitudinal edge portions 12 are inturned and stitched as at 14, thus forming a tubular structure 15 having a longitudinal extension 16. As shown in Fig. 3, the end portion of the stay 11 is inserted part 15 way into the tubular structure 15, after a suitable cement or adhesive substance has been applied to said end portion. The structure 15 is then folded over the end portion of the stay and cemented thereto, as shown in Fig. 4.

20 A pair of the stays each capped or covered in the manner described, is arranged and secured in a pocket structure presently to be described. A strip 17 of reenforcing textile material is laid against the material of the garment on the inside thereof in the present case. The stays are laid on the strip 17. A second strip 18 of textile material, which serves as a covering, is laid over the stays. Both strips 17 and 18 extend beyond the opposite ends of the stays. The strips 17 and 30 18 are stitched to the material of the corset and this stitching takes in the extensions 16. After stitching the parts to a point below the upper reenforcing and padding material, the material of the corset is pushed upwardly relatively to the stays, which gives a certain amount of fullness 35 without wrinkling the material. The stitching is then continued until the strips 17 and 18 together with the lower reenforcing and padding caps, are stitched to each other to complete the incorporation of the stays 11 with the lines of 40 stitching 19.

The opposite ends of stays 11 are thus secured to the material of the corset while the major intermediate portions of the stays are free in the 45 pockets formed by the stitched strips 17 and 18. The aforesaid fullness eliminates a condition in which the stays 11 would be kept abnormally flexed due to possible shrinkage of the material of the corset by washing the same, or from sweat.

50 I claim:

1. A stay of the character described comprising a strip of resilient material, and means only on each end portion of said strip for performing the following functions, namely, securing the 55 stay, reenforcing the securement, and preventing

the ends of the stay from puncturing the material to which the stay is secured, said means consisting of textile material folded upon itself secured to and completely covering said end portion leaving the remaining intermediate portion of the strip uncovered and providing an edge portion extending longitudinally of the stay and adapted to receive stitching.

2. The combination with a garment having a

stay pocket, a stay arranged within said pocket, said stay comprising a strip of resilient material, and a textile covering serving as a protecting cap on each end portion of the stay leaving the remaining intermediate portion uncovered, and said covering having a side edge portion which is secured to the material of the pocket and the garment.
